CLAIM

The ornamental design for a shower stall, as shown and described.

DESCRIPTION

FIG. 1 is a right, top, front perspective view of a shower stall embodying our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view taken along line 8—8 of FIG. 4;

FIG. 9 is a cross-sectional view taken along line 9—9 of FIG. 2;

FIG. 10 is a cross-sectional view taken along line 10—10 of FIG. 2;

FIG. 11 is a cross-sectional view taken along line 11—11 of FIG. 2;

FIG. 12 is a front elevational view of a second embodiment, the top plan view being identical to that shown in FIG. 4, and the other non-sectional views being mirror images of those shown in FIGS. 3 and 5-7; and,

FIG. 13 is a cross-sectional view thereof, the view being a mirror image of that shown in FIG. 11.
